Patented Oct. 12, 1920.

John Curtis Blue, Inventor
By his Attorney, F. W. Bunker

UNITED STATES PATENT OFFICE.

JOHN CURTIS BLUE, OF BROOKLYN, NEW YORK.

PRINTING-MACHINE.

1,355,531.

Specification of Letters Patent. Patented Oct. 12, 1920.

Application filed June 3, 1920. Serial No. 386,398.

To all whom it may concern:

Be it known that I, JOHN CURTIS BLUE, a citizen of the United States, and resident of Brooklyn, in the county of Kings and 5 State of New York, have invented certain new and useful Printing-Machines, of which the following is a specification.

This invention relates to printing machines using movable types and my im- 10 provement is directed particularly to types for ruling lines in connection with the multigraph machine, in which longitudinal channels upon the segmental drum receive the character types and the line producing 15 types lie circumferentially upon the drum or transversely across said longitudinal channels.

Hitherto difficulty has been experienced in locking these line rules in their set positions, which may be such as for the production 20 by said rules of lines separating columns of type matter—for margins, and for other purposes, because the anchorage they receive is provided by the abutment thereon 25 of character types under the locking engagement of spring clips, or by the direct abutment thereon of the clips. Under these forms of engagement the line rules are insecurely held, and are apt to either fall out 30 of place in the operation of the machine, or to become distorted from their true linear direction.

Therefore my invention consists in the provision of more secure anchorage means, 35 wherein the line rule is accorded a substantial base portion that it may have firm seating upon the rail surfaces, and also wherein lateral lugs, extending from one or both sides of said base portion, further enlarge the seating capacity of said rule. Furthermore these lateral lugs are distanced apart sufficiently to provide between adjacent lugs recesses adapted to receive the 40 mount portions of character type, or slugs if character types are not employed; or else the clips themselves may fit within these recesses, in order that in any one of these instances, frictional abutment of the adjacent member against the side of the line rule, 45 and its engagement within the recess provided by a pair of lugs, may firmly lock the line rule in its desired operative position.

In the drawing:

Figure 1 is a plan view of a drum seg- 50 ment, forming part of a multigraph ma- chine.

Fig. 2 is an end view thereof, partly in section.

Fig. 3 is a partial plan view, enlarged.

Fig. 4 is a section on the line 4—4 of Fig. 60 3, and

Fig. 5 is an enlarged cross-section of a line rule.

In said figures let 1 indicate the type-holding segment of a drum such as comprising 65 part of a multigraph machine, said segment having the spaced, parallel rails 2 extending longitudinally thereof, with the under-cut channels 3 for engaging the base portions 4 of types 5, or of slugs 5^a, and for 70 similarly engaging the shanks 6 of spring clips 7, these elements and members being of the usual known character.

My improved line printing type or rule consists of a strip of suitable material, 75 curved lengthwise to conform to the circumferential contour of the drum segment, over its rail surfaces, to seat thereon, and being of any desired length, said strip being of printing height, and having a relatively thin, outwardly tapered upper portion 8, for line printing, and a relatively thick lower portion 9, with a flat base 10, whereby said strip may be firmly seated upon and across rails 2. Also, extending laterally from one or both sides of said portion 9 are a number of lugs 11, said lugs occurring at such spaced intervals apart as to each lie centrally over a rail 2. This does not mean that the lugs 11, at each side of a 90 strip, must necessarily equal the number of rails spanned by the rule strip, but preferably each pair of lugs should lie over adjacent rails. The lug bases are flush with the strip base 10, because it is a function of the 95 lugs that they should augment the firm seating characteristic of the strip upon the rail surfaces, to maintain the upright position of the strip thereon.

Also, each pair of lugs 11, lying upon 100 adjacent rails, present between them a recess for the reception of a type or a slug, which may thus be frictionally engaged between said pair of lugs and also abut against the inclosed side portion of the line printing strip; the types or slugs, or both, being held from slippage by a usual clip 7.

Obviously, when a line printing strip is thus held at both sides thereof it is securely anchored in its set position, and is thus 110 capable of giving efficient service.

In some instances a clip 7 may be engaged

in abutting relation with the line printing strip, in a recess between lugs 11, to thus provide the desired anchorage without the use of character types or slugs.

- 5 When it is desired to produce horizontal lines with my line ruling device, as for under-scoring and other purposes, the line rule may be anchored in place upon a rail by causing either types, slugs, or clips, held 10 in adjacent rail grooves, to abut against the line rule at either side thereof.

I claim:—

1. A sectional printing rule for type-holding, rail surfaced drums, said rule having an upper printing surface, a seating base to lie upon the upper surface of a drum rail, and a series of thin vertical lugs, whose bases are solely in the plane of the rule seating base, and arranged to lie each upon a 20 rail surface within its span, to assist in maintaining the rule perpendicular to the drum surface.

2. A segmental printing rule for type-holding, railsurfaced drums, said rule having an upper printing surface, a seating base, and laterally extending lugs, adjacent lugs providing a recess for the lodgment of a lock member in abutting relation with said rule.

3. A segmental printing rule for type-holding, rail-surfaced drums, said rule having an upper printing surface, a seating base, and laterally extending lugs to co-act with the drum rails as seating elements, adjacent lugs providing a recess for the lodgment of a lock member in abutting relation with said rule. 30

4. In a multigraph machine, having a drum segment with spaced parallel rails and means for adjustably engaging character types, in combination, a line printing rule in segmental form, said rule having a substantial base portion whereby it may lie upon and across said rails, and an upper printing portion, also said base portion having laterally projecting lugs spaced apart so that they may lie in seating relation centrally upon the surfaces of adjacent rails, whereby the vertical position of the rule is firmly maintained and whereby adjacent lugs provide a recess for the reception of a slidable type or slug, to be locked therein in abutting relation with said rule. 40

Signed at the borough of Manhattan, in the city, county, and State of New York, 55 this 1st day of June, A. D. 1920.

JOHN CURTIS BLUE.
